(57) **CLAIM**

The ornamental design for a buckle, as shown and described.

DESCRIPTION

FIG. 1 is a perspective view of a buckle of a first embodiment of the claimed design.

FIG. 2 is a front elevational view of the buckle of FIG. 1.

FIG. 3 is a rear elevational view of the buckle of FIG. 1.
FIG. 4 is a top plan view of the buckle of FIG. 1.

FIG. 5 is a bottom plan view of the buckle of FIG. 1.
FIG. 6 is a right side view of the buckle of FIG. 1, and the left side view is a mirror image thereof.

FIG. 7 is a cross-sectional view of the buckle FIG. 2 taken along the line 7—7.

FIG. 8 is a cross-sectional view of the buckle of FIG. 2 taken along the line 8—8.

FIG. 9 is a front elevational view of a male member of the buckle of FIG. 1.

FIG. 10 is a rear elevational view of the male member of FIG. 9.

FIG. 11 is a top plan view of the male member of FIG. 9.
FIG. 12 is a bottom plan view of the male member of FIG. 9.

FIG. 13 is a right side view of the male member of FIG. 9, and the left side view is a mirror image thereof.

FIG. 14 is a cross-sectional view of the male member FIG. 9 taken along the line 14—14.

FIG. 15 is a front elevational view of a female member of the buckle of FIG. 1.

FIG. 16 is a rear elevational view of the female member of FIG. 15.

FIG. 17 is a top plan view of the female member of FIG. 15.

FIG. 18 is a bottom plan view of the female member of FIG. 15.

FIG. 19 is a right side view of the female member of FIG. 15, and the left side view is a mirror image thereof.

FIG. 20 is a cross-sectional view of the female member of FIG. 15 taken along the line 20—20.

FIG. 21 is a perspective view of a buckle of a second embodiment of the claimed design.

FIG. 22 is a front elevational view of the buckle of FIG. 21.

FIG. 23 is a rear elevational view of the buckle of FIG. 21.

FIG. 24 is a top plan view of the buckle of FIG. 21.

FIG. 25 is a bottom plan view of the buckle of FIG. 21.

FIG. 26 is a right side view of the buckle of FIG. 21, and the left side view is a mirror image thereof.

FIG. 27 is a cross-sectional view of the buckle of FIG. 22 taken along the line 27—27.

FIG. 28 is a cross-sectional view of the buckle of FIG. 22 taken along the line 28—28.

FIG. 29 is a front elevational view of a male member of the buckle of FIG. 21.

FIG. 30 is a rear elevational view of the male member of FIG. 29.

FIG. 31 is a top plan view of the male member of FIG. 29.

FIG. 32 is a bottom plan view of the male member of FIG. 29.

FIG. 33 is a right side view of the male member of FIG. 29, and the left side view is a mirror image thereof.

FIG. 34 is a cross-sectional view of the male member of FIG. 29 taken along the line 34—34.

FIG. 35 is a front elevational view of the female member of the buckle of FIG. 21.

FIG. 36 is a rear elevational view of the female member of FIG. 35.

FIG. 37 is a top plan view of the female member of FIG. 35.

FIG. 38 is a bottom plan view of the female member of FIG. 35.

FIG. 39 is a right side view of the female member of FIG. 35, and the left side view is a mirror image thereof; and, FIG. 40 is a cross-sectional view of the female member of FIG. 35 taken along the line 40—40.
